(57) **CLAIM**

The ornamental design of a handle cover, as shown and described.

DESCRIPTION

FIG. 1 is an isometric view from the front and to one side of a first embodiment of a handle cover;

FIG. 2 is a front elevation view of the handle cover of FIG. 1;

FIG. 3 is a rear elevation view of the handle cover of FIG. 1;

FIG. 4 is a side elevation view of the left side of the handle cover of FIG. 1 (when viewed from the front);

FIG. 5 is a side elevation view of the right side of the handle cover of FIG. 1;

FIG. 6 is a top plan view of the handle cover of FIG. 1;

FIG. 7 is a bottom plan view of the handle cover of FIG. 1;

FIG. 8 is an isometric view from the front and to one side of a second embodiment of a handle cover;

FIG. 9 is a front elevation view of the handle cover of FIG. 8;

FIG. 10 is a rear elevation view of the handle cover of FIG. 8;

FIG. 11 is a side elevation view of the left side of the handle cover of FIG. 8 (when viewed from the front);

FIG. 12 is a side elevation view of the right side of the handle cover of FIG. 8;

FIG. 13 is a top plan view of the handle cover of FIG. 8; and,

FIG. 14 is a bottom plan view of the handle cover of FIG. 8.

The broken lines shown in the drawings illustrate portions of the handle cover in which the design is embodied that form no part of the claimed design.

1 Claim, 14 Drawing Sheets
